BRAKE-LINING.

1,120,617.

Specification of Letters Patent.

Patented Dec. 8, 1914.

Application filed May 22, 1914. Serial No. 840,249.

To all whom it may concern:

Be it known that I, WILLIAM G. HOFMANN, a citizen of the United States, residing at Milford, county of New Haven, 5 State of Connecticut, have invented an Improvement in Brake-Linings, of which the following is a specification.

This invention has for its object to produce a lining or friction material, especially 10 adapted for use in automobile brakes, and for friction shoes, clutch pads, &c., where a high coefficient of friction is required and where there is great pressure and tendency to develop heat. With this end in view, 15 I have devised the novel friction lining which I will now describe, in which longitudinal grooves are provided in the operative surface to serve as channels for oil in the class of brakes which run in oil; and as 20 air spaces in brakes where no oil is used.

In the accompanying drawing forming a part of this specification, the figure is a perspective illustrating my novel lining.

The fabric is made by weaving asbestos 25 yarn, which may or may not as preferred have a wire strand, about a plurality of relatively large filling cords, then treating the woven fabric by immersion in a hardening compound and then hot-calendering the 30 treated fabric by passing it through hot calendering rolls, one of which is smooth and the other ribbed and grooved to permanently form in the fabric longitudinal channels between the cords.

35 10 denotes woven asbestos yarn, 11 the filling cords, and 12 the channels in the fabric between the cords. The weaving may be done upon an ordinary asbestos loom set up with the filling cords properly spaced 40 apart and running in the direction of the warp threads. Any number and size of the filling cords may be used, depending of course upon the width of the strip of fabric to be woven and the special use for which it 45 is intended. The special hardening compound used is immaterial so far as the present invention is concerned. It is sufficient for the purposes of this specification to state that the fabric as completed by the loom is 50 treated by immersion in any suitable hardening compound. If preferred, and in order to shorten the time required for suitably treating the completed fabric, the cords may be treated by immersion in the harden-

ing compound before being set up in the 55 loom.

After the hardening treatment, the channels are permanently formed in the operative side of the lining between the cords by passing it between hot calendering rolls, one 60 of which is smooth and the other provided with grooves to receive the asbestos covered cords and with ribs which permanently form the channels. The effect of this calendering operation is to partly dry and to permanently 65 harden and set the fabric, the channels formed between the cords in the completed lining being permanent and lasting as long as the fabric itself.

It is of course well understood that asbestos fabrics for brake linings and similar uses after the hardening treatment will not absorb oil, and consequently that as these fabrics have heretofore been woven there is little space for oil between the lining and 70 the surface with which it co-acts. This objection is wholly overcome in my novel lining, as the channels between the cords hold an appreciable quantity of oil which necessarily comes into contact with the brake 75 drum and is effectually spread over the surface of the drum by centrifugal action.

My novel brake lining is equally effective upon the class of brakes that do not run in oil, as the channels serve as air spaces and 80 the air contained therein acts to a marked degree in reducing the heat generated by the frictional contact of the lining with the drum.

Having thus described my invention I 85 claim:

1. A lining of the character described formed from woven asbestos and impregnated with a hardening compound and having its operative face provided with longitudinal channels.

2. A lining of the character described formed from asbestos woven about spaced apart longitudinally disposed cords and treated with a hardening compound and 100 having formed in its operative face longitudinal channels between the cords.

3. The process of making fabric for brake linings and similar uses which consists in weaving asbestos yarn about spaced apart 105 longitudinally disposed cords, then immersing the fabric in a hardening compound and finally rolling the same under heat and

forming in the operative face thereof longitudinal channels between the cords.

4. The process of making fabric for brake linings and similar uses which consists in immersing the cords in a hardening compound, spacing said cords apart and weaving asbestos yarn about them, then immersing the fabric in the hardening compound and finally rolling the same under heat and

forming in the operative face thereof longitudinal channels between the cords. 10

In testimony whereof I affix my signature in presence of two witnesses.

WILLIAM G. HOFMANN.
